UNITED STATES PATENT OFFICE.

HANS HENRIK BLACHE, OF HELLERUP, NEAR COPENHAGEN, DENMARK.

DOUBLE-ACTING FOUR-STROKE DIESEL MOTOR.

Application filed April 27, 1923. Serial No. 635,113.

To all whom it may concern:

Be it known that I, HANS HENRIK BLACHE, a subject of the King of Denmark, residing at Hellerup, near Copenhagen, Denmark, have invented certain new and useful Improvements in a Double-Acting Four-Stroke Diesel Motor, of which the following is a specification.

This invention relates to a four-stroke Diesel motor constructed as a double-acting engine which has not hitherto been possible as it has been impossible to find the necessary room for all the valves of the four-stroke engine (exhaust, inlet, fuel and starting valve) in the bottom of the cylinder in which not only the valves but also the very heavy piston rod is to be mounted.

The invention relates to a four-stroke Diesel motor constructed in such a way that it may be built as double-acting. This is obtained by removing the valves from their normal place in the bottom of the cylinder and building them into a special chamber acting as a compression chamber and placed 25 at one side of the cylinder level with the bottom thereof. The employment of a special valve and compression chamber at the side of the cylinder is possible if the bottoms of the piston and the cylinder are so formed that, in the lowermost position of the piston, the clearance space between the latter and the bottom of the cylinder is as small as possible, so that the total compression volume is not increased beyond about 30 8% of the cylinder volume necessary to the compression volume.

The arrangement of valves in a chamber at one side of a cylinder is known per se e. g. from automobile motors but has not been 40 previously used as a means whereby four-stroke Diesel motors may be built as double-acting.

The novel feature of the invention is partly the arrangement of the valves in the 45 special compression chamber at one side of the cylinder with the necessity arising therefrom of causing the piston to go wholly down, partly the special assembling of the cylinder and its bottom with the water jacket of the same necessitated by the side chamber. The water jacket is carried at 50 its lower part by the machine frame and the cylinder with integral parts is suspended in or carried by the jacket so that, owing to 55 the valve chamber being placed at the side, the dismounting of the parts must be carried

out by assembling the cylinder and annexed parts with the water jacket at the top end of the cylinder and by a packing box or other suitable packing around the lower end of the cylinder, while the upper portion of the water jacket is not made in one piece but divided by a longitudinal flange, enabling that part of the water jacket which is above the special compression chamber at 60 the side of the cylinder to be loosened and removed. 65

By the above-described construction double-acting four-stroke Diesel motor may be built, which means also that by the same 70 dimensions of the cylinder almost twice the work of the hitherto known four-stroke Diesel motors may be obtained. Furthermore the cylinder bottom, which has no 75 openings for the great valves, is very resistant against the tensions caused by the heat.

In the drawing is represented a constructional form of the invention.

Fig. 1 is a sectional elevation of the entire 80 construction.

Fig. 2 is an elevation of the special compression chamber with the valves, and,

Fig. 3 is an elevation of the upper portion 85 of the water jacket and the flange by which the halves of the jacket are tightened together.

In Fig. 1, A is the cylinder which is integral with the bottom B. As the drawing shows, the bottom B has only one opening, 90 namely that in which the piston rod C and its packing box are mounted. The drawing shows the piston D in its lower dead point in which position there is only the necessary very little space between the piston and the bottom of the cylinder. According to the invention, all valves are assembled in a 95 special compression chamber F placed at the side of the lower part of the cylinder.

The compression chamber F communicates with the interior of the cylinder and contains, as shown in Figs. 1 and 2, the four valves, viz the suction valve G, the exhaust valve H, the fuel valve I and the starting valve K, Fig. 2. 100

The cylinder bottom itself is double, both for the sake of strength and for the purpose of forming part of the water jacket. The exterior wall of the cylinder bottom is extended upwardly so as to form a circular flange L, Fig. 1. The entire cylinder construction is surrounded by and carried in 105 110

the cylinder jacket P which rests at its bottom on the machine frame. The upper portion of the jacket is divided into two halves connected with each other by a vertical assembling flange as shown in Fig. 3 which represents the same jacket as in Fig. 1 but seen from its outer side. The cylinder A, Fig. 1, is provided at its top in the usual manner with a projection N resting on a corresponding projection O on the cylinder jacket P. The projections N and O are tightened together by the top plate Q which is in the usual manner fixed to the jacket P by a suitable number of bolts R and provided with a rib S entering the upper edge of the cylinder wall. The entire space between the jacket and the cylinder and the great compartment in the cylinder bottom are employed as a cooling jacket for the cylinder. The tight joint between the cylinder jacket P and the flange L of the cylinder is obtained by a packing box T or another suitable packing.

I claim:

1. In a double-acting four-stroke Diesel engine having its cylinder liner suspended at its top so as to be free to expand down-

wardly, in combination, a cylinder liner, a bottom cover formed integrally with the cylinder liner and formed to receive a piston rod, a valve chamber integral with the combined cylinder liner and bottom cover, all necessary valves being fitted in the valve chamber, a flanged cooling jacket formed of a plurality of pieces and constituting a part of the engine frame and so connected to the cylinder bottom as to permit free expansion downwardly of the cylinder liner and valve casing relative to the cooling jacket.

2. In an engine according to claim 1, an annular projection on said cooling jacket, when assembled, suspending the upper end of said cylinder liner, and an upper cover fastened to the cooling jacket.

3. In an engine according to claim 1, said cylinder bottom having a sliding connection with said cooling jacket forming part of the engine frame, so as to permit free downward expansion of said cylinder liner and valve casing relative to the cooling jacket.

In testimony whereof I affix my signature.

HANS HENRIK BLACHE.
